UNITED STATES PATENT OFFICE.

HUTCHINSON BEVIER AND JULES J. DURAGE, OF DULUTH, MINNESOTA.

EXPLOSIVE POWER-GENERATOR.

No. 850,992.

Specification of Letters Patent.

Patented April 23, 1907.

Application filed July 6, 1905. Serial No. 268,475.

To all whom it may concern:

Be it known that we, HUTCHINSON BEVIER and JULES J. DURAGE, citizens of the United States, residing at Duluth, in the county of 5 St. Louis and State of Minnesota, have invented certain new and useful Improvements in Explosive Power-Generators; and we do hereby declare the following to be a full, clear, and exact description of the invention, 10 such as will enable others skilled in the art to which it appertains to make and use the same.

Our invention relates to explosive power-generators, and has for its object the provision, in combination with a floating vessel or support, of an improved generator for generating a propelling-gas and for applying it directly for motive purposes against the water through which the vessel is propelled.

20 It consists, in combination with a vessel or floating support, of a gas-generating and combustion chamber, means for charging said chamber with hydrocarbon and air, means for igniting said hydrocarbon in the presence 25 or in mixture with said air, and tubes leading from said generating-chamber to the water in which said vessel is floated.

It also consists of certain other constructions, combinations, and arrangements of 30 parts, as are hereinafter described and claimed.

In the drawings, Figure 1 is a vertical longitudinal section of said invention on the line *a b* of Fig. 2, omitting the containing vessel or support. Fig. 2 is a reduced transverse section of a vessel, showing a rear elevation, partly in vertical transverse section, of said invention. Fig. 3 is a reduced detail transverse section of our said invention between 40 the lines *c d* and *x y* of Fig. 1. Fig. 4 is a reduced diagrammatic view of a portion of said vessel and of said invention, showing the arrangement of the propelling and backing tubes of said invention. Fig. 5 is a reduced vertical longitudinal section of a portion of said vessel on the line *s t* of Fig. 2, showing a side elevation of said invention, partly in vertical longitudinal section. Fig. 45 6 is a reduced vertical transverse section of a portion of said invention on the line *g h* of Fig. 1. Fig. 7 is a reduced horizontal section of said invention on the line *m n* of Fig. 1.

In the drawings, 1, 1^a, and 1^b are parts of a gas-generating chamber. Through said part 1 extends a flue 2, and positioned in said part 1 above said flue is a grate 3. Said chamber is provided with a port 1^c for admitting hydrocarbon into said chamber and with a port 1^d for admitting air to said chamber. Extending from said chamber are two 60 tubes, as 4 and 5, communicating with said chamber through ports 4^a and 5^a, formed in the walls thereof. Said ports 4^a and 5^a are governed by any suitable valve construction or constructions adapted to open the port 4^a 55 and close the port 5^a, or vice versa, as preferably by a valve 6, pivotally mounted in said chamber and provided with an outwardly-extending valve-stem 6^a and operating-lever 6^b, which valve is adapted in one position to 70 close the mouth of the port 4^a and in another position to open the port 4^a and close the port 5^a. Said tube 4 is designed to lead forwardly to and through the bow or the side of the vessel 7 below the water-line thereof, and 75 said tube 5 is designed to lead rearwardly to and through the stern of the vessel below the water-line thereof. Said chamber is also preferably provided with a port 8, normally closed by a safety-valve 8^a, held down 80 on its seat by a spring 8^b, adapted to be raised by any excess power-pressure in said chamber. Said chamber is also preferably provided with one or more natural-draft air-ports 9, governed by normally open valves 85 9^a, adapted to be closed by any explosive pressure within said chamber. Carried by said vessel is a hydrocarbon-reservoir 10, connected by a tube 11 with the port 1^c. Said tube 11 is provided with any suitable 90 current-governing valves, as 12, adapted to permit or to cut off the flow of hydrocarbon through said tube. Said port 1^d is governed by any suitable check-valve 1^e, adapted to be closed by explosive pressure from within said 95 chamber. A lamp or torch 14 is positioned within a suitable hood or housing 15, with which said flue 2 communicates. The opposite end of said flue preferably communicates with a chimney-flue 2^a, extending outwardly 100 of said chamber. Said port 1^d by means of a tube 16 and said housing 15 by means of a tube 15^a communicate with a fan-chamber 17, preferably at the periphery of said fan-cham-

ber. Said fan-chamber has journaled there-in a fan or blower 18 of any suitable construction, adapted to be run by any suitable motive means—as, for example, a clockwork mechanism comprising the spring 19, the shaft 20, the tight ratchet-wheel 21, mounted on said shaft, the loose gear-wheel 22, mounted on said shaft, the pawl 23, pivoted to said gear 22 and engaging the teeth of said ratchet 21, the gear 24, meshing with said gear 22 and rigidly fixed on the blower or fan shaft 25. Said fan-chamber is provided with an inlet port or ports 26, adapted to admit air to said chamber. Said valve 12 is provided 15 with a valve-operating rocker-arm 12^a, adapted to be operated in any suitable manner by said motor, as by a reciprocating arm 27, pivotally connected at one end to said rocker-arm and at its opposite end connected to an 20 eccentric 28, mounted upon a shaft 29, journaled in suitable supports 30. Said shaft 29 is provided at its opposite end with a sliding rotatable gear 31, adapted in operating position to engage a gear 32, mounted upon the 25 shaft 20. The outer end of said shaft 20 is formed into a winding-stem adapted to engage the winding-key 33, which key is preferably provided with a beveled shoulder or collar 33^a, adapted during the winding operation to disengage said gear 31 from said gear 32. The gear 31 is normally held in operative 30 position by a spring of any suitable construction, as 34. Below said port 1^d, which, it may be observed, is below the port 1^c, there 35 is formed on the inside wall of said chamber 1 a lip 1^f, adapted to catch the drip from the port 1^e and retain it in such relation to the port 1^d that the incoming air through the port 1^d will scatter and vaporize it and mix 40 with it. Said lamp or torch is also connected with said tank by means of a tube 35, and suitable manually-operated cut-off valves, as 36, are mounted in the tubes 11, 16, 15^a, and 35 to permit of the supply of hydrocarbon or 45 blown air being arbitrarily regulated or cut off from said chamber 1 or from said torch, or both. Said generators, tanks, and power-applying tubes and governing-valves may be 50 single or double or otherwise, as desired, and in the drawings certain portions are shown in duplicate, certain other portions, as the motor, being single or adapted to use in common by two generators.

In operation the torch is lighted and the 55 flue 2 heated to gas-igniting heat. The motor is then started, thus admitting to the chamber 1 a charge of hydrocarbon and simultaneously a forced draft of air in proper proportions to make an explosive mixture, 60 which is thereupon ignited or exploded by the heated flue 2. The expanding gas seeking to escape through the tube 4^a or 5^a, as the

case may be, pushes directly against the water, thus backing the vessel or propelling it ahead, as the case may be. After the chamber 1 is thoroughly heated and the grate 3 is thoroughly heated by explosions of gas it is believed that said torch may be extinguished without stopping the engine. The volume of air blown into said chamber and the amount 70 of hydrocarbon admitted thereto may be readily regulated by means of the said manually-operated valves 36. It will be observed that the generators contain no power-pistons and that they are always in direct communication through one or the other of the tubes 4 or 5 with the water surrounding the vessel. We do not desire, however, to be restricted to the especial form of motor, as said clock mechanism, shown or described or to the particular forms of valves, it being evident that 75 various minor or convenient modifications may be made in said constructions without departing from the spirit or scope of our invention.

Having now described our invention, what we claim, and desire to secure by Letters Patent, is—

1. In an explosive power-generator, the combination with a vessel or floating support, of a gas-generating and combustion chamber adapted to communicate at all times directly with the water surrounding said vessel, means including a clockwork mechanism, and blower, adapted to introduce a charge of air into said generating-chamber, means for separately introducing a charge of hydrocarbon into said chamber, and means adapted to ignite said charges in mingled condition in said chamber.

2. The combination of a combustion-chamber provided with an admission-port adapted to admit hydrocarbon to said chamber, and with an admission-port adapted to admit air to said chamber, and with a lip formed upon the inner face of said chamber below both of said ports and adapted to catch the drip of the first said port and expose it to the draft of incoming air through the second said port, means adapted to force air into said chamber through the second said port, communicating means open at all times between said chamber and a surrounding liquid, means adapted to introduce hydrocarbon to said chamber, and means adapted to explode the mixture of air and hydrocarbon in said chamber.

3. The combination of a combustion-chamber having a constant communication with free water, means adapted to introduce air under pressure into said chamber, means for introducing air under natural atmospheric pressure into said chamber, a lip formed on the wall of said chamber to catch the hydro-

carbon charge and expose it to the forced draft of air, means adapted to introduce hydrocarbon into said chamber, a flue extending through said chamber, means adapted to heat said flue to gas-igniting heat, and means for regulating the volume of forced air and hydrocarbon introduced into said chamber.

In testimony whereof we hereunto affix our signatures in presence of two witnesses.

HUTCHINSON BEVIER.

JULES J. DURAGE.
